United States Patent

Des. 241,587
Patented Sept. 28, 1976

241,587

BASEBALL GLOVE

Kozo Takebayashi, Kaohsiung, Taiwan, assignor to Sakurai International, Inc., Santa Ana, Calif.

Filed May 27, 1975, Ser. No. 573,910

Term of patent 14 years

Int. Cl. D2—06

U.S. Cl. D2—361

FIG. 1 is a perspective view of the front side of a baseball glove showing my new design;

FIG. 2 is a perspective view of the backside of the baseball glove, taken toward the fingertips; and

FIG. 3 is a perspective view of the backside of the baseball glove, taken toward the hand opening.

I claim:

The ornamental design for a baseball glove, as shown.
